Charles A. Birch-Field
William S. Ghet
ATTORNEY

UNITED STATES PATENT OFFICE.

CHARLES A. BIRCH-FIELD, OF LARCHMONT, NEW YORK.

ELECTRIC APPARATUS.

Application filed September 26, 1922. Serial No. 590,561.

To all whom it may concern:

Be it known that I, CHARLES A. BIRCH-FIELD, a citizen of the United States, residing at Larchmont, county of Westchester, State of New York, have made a certain new and useful Invention in Electric Apparatus, of which the following is a specification.

This invention relates generally to electric apparatus and more particularly to the utilization of such apparatus for the reception of impulses at radio frequencies and their conversion into impulses at audio frequencies.

While my apparatus as a whole is intended for utilization in connection with the reception of electric impulses at radio frequencies, it will be understood of course that elements and parts thereof are capable of utility in relationships other than that herein pointed out, and as to such other relationships, the embodiment shown in the drawings is intended only as illustrative and not as limitative.

In radio receiving sets generally and more particularly in the less expensive sets, great difficulty is encountered in the reception from stations at a distance and even in stations close by, due among other things to a lack of sharp tuning capabilities in the parts of such sets, and among the more important objects of this invention is the provision of a receiving set which is inexpensive in cost and nevertheless capable of very sharp and quick tuning and very efficient detuning.

Where such receiving apparatus employs the inductive relationship of two induction members, such as coils, it is obvious that the efficiency of the inductance will be dependent upon the extent to which the secondary cuts the lines of force about the primary and this is a prime consideration in the mounting of induction members.

Among other important objects of my invention therefore are; the provision of a circuit for the reception of electric impulses at radio frequencies which is simple in character and of a hook up which is efficient in operation and cheap to man-

facture; the provision of a circuit for the reception of electric impulses at radio frequencies in which the grid leak condenser and secondary are each connected directly to the variable condenser; the provision of inductance members so related and associated that the secondary may be positioned in any desired portion of the field about the primary; the provision of inductance members so associated as to permit of their variation in position relatively to each other, so as to give maximum inductance; the provision of inductance members so arranged and associated as to permit of rapid and sharp tuning when employed as part of an apparatus for the reception of electric impulses at radio frequencies; the provision of inductance members so mounted and associated as to permit of the variation of their relative positions in more than one plane and more particularly to permit of such variation by the operation of but one control; the provision of inductance members so mounted and associated as to permit of angular variation therebetween in a plurality of planes; the provision of inductance members so arranged and associated that a relative bodily universal movement can be given the members; the provision of inductance members related and associated as set forth above, at least one of which inductance members is in the form of a flat coil; the provision of relatively movable induction members one of which is in the form of a flat coil; the provision of a flat or spider web coil having one of its flat faces provided with an insulating covering; the provision of relatively movable induction members, one of which is in the form of a flat coil covered on one side with insulation the other side being positioned adjacent the other member and more particularly of such a coil tapped through the insulation; and the provision generally of a new and simplified receiving apparatus and of a new improved and inexpensive arrangement of induction coils therefor.

In attaining the objects referred to and gaining certain other benefits and advantages that will appear or that will be below pointed out, I have provided a con-

struction, one embodiment whereof is illustrated in the accompanying drawings wherein:

Figure 1 is a diagrammatic view of a circuit in which my invention may be embodied;

Figure 2 is a section through the induction members;

Figure 3 is a view of a portion of the front face of a box in which my apparatus may be received, partly broken away;

Figure 4 is a section showing a modification;

Figure 5 is a view taken on line 5—5 of Figure 4 looking in the direction of the arrows.

Upon viewing Figure 1 it will be observed that I have here shown diagrammatically a receiving apparatus in which 10 is the antenna, 11 the primary, 12 the ground and 13 the taps for tuning the antenna circuit; The secondary is illustrated as 15, 16 being the variable condenser, 17 the grid lead condenser, 18 the detector lamp, 19 the battery, 20 the B battery and 21 the ear phones.

Although I have illustrated in the various figures the primary coil as tapped for tuning, it will be understood that this is not essential as the secondary may be tapped instead or both may be tapped for this purpose. It will therefore be understood, as this specification is read, that the showing in the drawing in this respect is merely illustrative;

As will be observed on viewing Figure 2, I employ for tuning purposes the induction members 25 and 26 these members being mounted for movement relatively of each other in a plurality of planes and in a plurality of directions as will be pointed out presently;

The element 27 is intended to show a portion of the support which for instance may be one of the walls of a container, which container may take any desired or preferred form. The induction members 25 and 26 may be supported from this wall 27, the induction member 25 being illustrated as immovably carried thereby and the member 26 as carried thereby for variation with reference to the member 25. As will be understood of course, this relative variation between the two induction members may be obtained regardless of which one is moved and in fact may be obtained upon an actual movement of both. As will be observed upon viewing Figures 2 and 3 I have shown the induction members 25 and 26 supported in a pendant position, the advantages of which will be obvious.

The induction members 25 and 26 are preferably in the form of flat or spider web coils, the fixed coil 25 being shown for purposes of illustration as the primary and the movable coil 26 as the secondary. For pur-

poses of tuning I provide one of the coils, in the drawing for illustration the coil 25 is so arranged, with leads 27 running to taps 28 which are thrown in successively by the manual control 29 for tuning purposes in an obvious manner. I have provided the tapped-coil with an insulated covering such as that illustrated at 30 in Figure 2 on that face which is farthest removed from the other coil, and have run the tapping leads 27 through this insulation 30.

The other induction member 26 which in the drawing is illustrated as the secondary, is supported for movement linearly and bodily toward and away from the other induction members 25 by being mounted for movement along the rod 31 which in turn is mounted for rotation in the bearing 32 which is hinged to the frame for pivotal movement about the horizontal axis 33. The linear movement of the coil 26 along the rod 31 may be attained in any desired or preferred manner as by means of the engagements between the nut 34 and the threaded portion 35.

It will therefore be understood that when the knurled portion 36 of the rod 31 is rotated in the bearings 32 the induction coil 26 will be moved angularly, parallel of the coil 25 and transversely of the magnetic field thereabout. Furthermore, when the rod 31 is moved about the hinge or pivot 33, the secondary 26 will be given a movement which is angularly toward and away from the coil 25. In this manner by the operation of the single control handle 36, I am enabled to give the induction members all relative positions so that the secondary may be so positioned with relationship to the various portions of the magnetic field that the desired sharp tuning and detuning may be quickly and simply attained. It will be understood that both movements can be given simultaneously and in fact it will be understood that one of the great advantages of this arrangement is not only that the magnetic field can be searched quickly and efficiently but that the secondary can be given any desired angular position therein.

In Figures 4 and 5 I have shown a modified construction for attaining the desired variability between the induction members in which the bearing member 32 is supported as shown in Figure 5.

I have found that by arranging the coils as set forth, not only is any desired character of inductance attained, but any point in the magnetic field of the primary can be quickly reached by the operation of the single control 36.

The employment of the pancake coil 25 insulated by the shield 30 and tapped as shown adds materially to the simplicity of the construction and to the good results attained by me. I have further found that by winding

the coils 25 and 26 in opposite directions, I attain results which generally are better than those attained when the coils are wound in the same direction.

5 Having thus described my invention and illustrated its use, what I claim as new and desire to secure by Letters Patent is:

1. In an inductance mounting, the combination with an inductance member, of a second inductance member, and means whereby said second member may be shifted angularly both transversely of, as well as toward and away from the field about said first member.

15 2. In an inductance coil mounting, the combination with an inductance coil of a second inductance coil, and means whereby said coils may be shifted relatively both parallel of each other, and angularly bodily toward and away from each other.

3. In an inductance coil mounting, the combination with a flat coil, of a second flat coil, and means whereby said coils may be shifted relatively both angularly parallel of each other and angularly bodily toward and away from each other.

4. In an inductance coil mounting, the combination with an inductance member of a second inductance member, and means whereby said members may be shifted relatively bodily angularly of each other in a plurality of planes.

25 5. In an inductance coil mounting, the

combination with an inductance coil of a second inductance coil, and means whereby 35 said coils may be shifted relatively bodily angularly of each other in a plurality of planes and linearly toward and away from each other.

6. In an inductance coil mounting, the 40 combination with an inductance member, of a second inductance member, and means whereby said second member may be shifted angularly, both transversely of, as well as toward and away from the field of said first 45 member, one of said inductance members being in the form of a flat coil.

7. In an inductance coil mounting, the combination with an inductance member of a second inductance member, and means 50 whereby said members may be shifted relatively bodily angularly of each other in a plurality of planes, one of said members being in the form of a flat coil.

8. In an inductance coil mounting, the 55 combination with an inductance member of a second inductance member, and means whereby said members may be shifted relatively bodily angularly of each other in a plurality of planes, and a single control for 60 giving said second member its different movements.

In testimony whereof I have hereunto signed my name.

CHARLES A. BIRCH-FIELD.
